ABSTRACT OF THE DISCLOSURE

A miniature sexless coaxial connector is characterized by an inner conductor sliding spring mechanism to establish coupling between like connectors while introducing negligible mismatch.

BACKGROUND OF THE INVENTION

The present invention relates to precision sexless miniature connectors and more particularly concerns a novel miniature coaxial connector suitable for use with 3.5 millimeter lines while introducing negligible mismatch or unwanted resonances.

The use of a spring-loaded inner conductor for a precision coaxial sexless connector is not in and of itself new. There exists such a connector for use in 7 mm. coaxial lines. However, practical difficulties are encountered when merely scaling down this connector to the 3.5 mm. size.

Accordingly it is an important object of this invention to provide a precision sexless coaxial connector suitable for use with 3.5 mm. lines that is reliable, relatively easy and inexpensive to fabricate and exhibits excellent electrical properties over a wide bandwidth.

It is a further object of the invention to achieve the preceding object while introducing relatively little mismatch over a wide range of frequencies.

SUMMARY OF THE INVENTION

According to the invention, there are means defining an outer conductor and an inner conductor assembly having an inside portion maintained in fixed relationship with respect to the other conductor means and an outside portion that is axially slideable and radially fixed relative to the axis of the connector. The inner conductor assembly includes spring means in a region around an outside stud that is inside the circularly cylindrical cavity at the inside end of the inner conductor outside portion. The bottom of this cavity is defined by an annular shoulder or base formed with an opening of diameter slightly larger than the diameter of the stud, but slightly less than the diameter of a screwhead. The stud is internally tapped to accommodate a screw having that screwhead so that the screwhead coats with the base to limit the outward movement of the outside portion as the surrounding spring urges the inside and outside portions apart to insure good contact with the inner conductor of a like sexless coaxial connector. The inside portion also includes a beveled shoulder upon which the inside surface of the outside portion rides.

Numerous other objects, advantages and features of the invention will become apparent from the following specification when read in connection with the accompanying drawing in which:

2

BRIEF DESCRIPTION OF THE DRAWING

FIG. 1 is a longitudinal sectional view through a connector according to the invention; and

FIG. 2 is a sectional view through the inner conductor assembly according to the invention.

DETAILED DESCRIPTION OF PREFERRED EMBODIMENTS

With reference now to the drawing and more particularly FIG. 1 thereof, there is shown a sectional view through a connector according to the invention. The outer conductor assembly includes a main **conducting** **conductive** portion 11 **that carries an annular dielectric bead 12 in the inside end of the connector surrounding an inner conductor inside** **which serves as the outer conductor of a coaxial line. The portion 11 is preferably a cylinder having extending through it a central longitudinal aperture 10. Adjacent one end of the cylinder and situated in the central aperture is an annular dielectric bead 12. The insulative bead supports the end portion 13 of inner conductor 14 to maintain the inner conductor coaxial with the outer conductor 11. The end portion 13 is of slightly smaller diameter than the main length of the inner conductor so that the characteristic impedance of the connector along the entire length is substantially constant. The inner conductor assembly includes a fixed inside portion 14 that is supported by three **radial insulator pins 15 which extend radially and are equiangularly disposed about the connector axis between compensating pairs of holes, such as** 16. **Where inner conductor 14 is relatively short, the support provided by the bead 12 is sufficient to hold the inner conductor 14 in rigid concentric relationship with cylinder 11 and the insulator pins need not then be employed.** The outer conductor assembly also **[carries]** **includes a crenelated alignment ring 17 at its outside end that is held in place, which protrudes beyond the cylinder 11 and is held in engagement with the cylinder by the internally and externally threaded collar 21. An internally threaded coupling nut 22 completes the outer conductor assembly.****

The inner conductor **[assembly]** 14 includes **[a moveable outside portion]** **an assembly 23 having a moveable cylindrical sleeve** that is slideable along the axis of the connector but maintained in precise concentric relationship with respect to the outer conductor.

Referring to FIG. 2 there is shown a detailed magnified longitudinal sectional view of the inner conductor assembly near the outside end of the connector helpful in understanding the invention. The unitary circularly cylindrically symmetrical conducting part 24 is formed with an outside stud 25 that fits snugly within the hollow end of **[assembly]** conductor 14 in fixed relationship thereto. That is, stud 25 is held to conductor 14 by any suitable means to prevent the disengagement of those members. **[Its outside end]** The protruding end of part 24 is formed with a stud 26 having a threaded opening 27 for accommodating a screw 31. A hollow conducting **[cylinder]** **cylindrical sleeve** 32, urged away from conducting member 24 by spring 30 and limited in axial end travel by the head of screw 31, completes the inner conductor assembly. **The sleeve 32 is, in effect, an extension of conductor 14.** A feature of the invention resides in forming the shoulder 33 of member 24 upon which the inside wall of member 32 slides slightly bevelled as shown to help reduce electrical mismatch. Member 32 is formed with a central opening 34 of diameter slightly greater than that of outside stud 27 and less than the diameter of the head of screw 31 and the diameter of spring 30. Actual contact with the inner conductor of a like mating connector occurs along the annular outer surface 35 as the spring

urges member 32 against a like member to insure good
iable contact.

Referring again to FIG. 1, actual connection occurs by
ding back the coupling nut 22 on one connector and
rewing the coupling nut of the other connector around
outside threads of member 21 [as the crenelated align-
ment rings and the two connector interleave and engage
e another]. *The crenelated rings engage and interleave
align the two connectors and the spring biased center
ductor sleeves 32 are pressed together, end to end, in
utting engagement to provide good electrical continuity
r the inner conductor.* The specific crenelated ring and
upling nut assembly is known in the art and is not a
rt of this invention.

The invention is relatively easy and inexpensive to fabri-
te. The member 24 may be accurately formed. Assembly
relatively easy to accomplish by putting spring 30 over
id 26, sliding member 32 over member 24, and screw-
; screw 31 into threaded opening 27.

There has been described a novel connector assembly
at represents a practical high performance 3.5 mm. sex-
is coaxial connector. It is evident that those skilled in the
; may now make numerous uses and modifications of
d departures from the specific embodiment described
rein without departing from the inventive concepts.
sequently, the invention is to be construed as embrac-
; each and every novel feature and novel combination
features present in or possessed by the apparatus and
chniques herein disclosed and limited solely by the spirit
d scope of the appended claims.

The bevelling of shoulder 33 performs a dual function.
provides a means for effecting good contact with the in-
le wall of hollow conducting cylinder 32 over a range
relative axial displacement. It also increases slightly
e effective diameter of the outer surface of cylinder 32
his cylinder having four longitudinal slots in space
adrature to permit some expansion) to introduce an
eactive capacity that compensates for the inductive effect
the gap d immediately adjacent to the cyinlder open end
d of the slots.

The slight difference between the diameter of opening
and stud 26 allows a slight axial misalignment of inner
ductors of mating connectors to insure a good con-
ction with good electrical characteristics despite slight
echanical imperfections.

What is claimed is:

1. A precision miniature coaxial sexless connector com-
ising:

[means defining an] a cylindrical outer [conducting
surface] coaxial conductor [having an inside axis],
an inner conductor axially disposed along the center
of the cylindrical outer conductor,
an inner conductor assembly disposed inside [said
means defining an] the cylindrical outer conductor
and in alignment with the inner conductor,
said inner conductor assembly including a cylindrical
conducting part having means at one end fixed to the

inner conductor, said conducting part having a [an
outside] stud of first diameter contiguous with a
shoulder of second diameter greater than said first
diameter [and formed with], said stud having an inter-
nally threaded opening for receiving a screw.
a hollow cylindrical conducting element open at one
end and having its inside wall axially slideable along
said shoulder, [and] said element having a base at
the other end formed with an opening of third diam-
eter slightly larger than said first diameter,
[spring] resilient means in the region between said
shoulder and said base urging said shoulder and said
base apart,
and a screw in said threaded opening having a head of
fourth diameter slightly greater than said third di-
ameter for limiting the axial displacement of said
base [.]
said base including a terminal annulus within which
the entire head of the screw is recessed.

2. A precision miniature coaxial sexless connector in
accordance with claim 1 wherein said shoulder is slightly
bevelled.

3. A precision miniature coaxial sexless connector in
accordance with claim 1 wherein said [spring] resilient
means is a helical spring surrounding said [outside] stud
and of fifth diameter greater than said third diameter and
less than said second diameter.

4. A precision miniature coaxial sexless connector in
accordance with claim 2 wherein said [spring] resilient
means is a helical spring surrounding said [outside] stud
and of fifth diameter greater than said third diameter and
less than said second diameter.

5. A precision miniature coaxial sexless connector in
accordance with claim 1 wherein said [outside] stud and
said shoulder comprise a unitary structure.

6. A precision miniature coaxial sexless connector in
accordance with claim 5 wherein said unitary structure
[comprise] includes an inside stud at its inside end
which is received within the inner conductor.
